HORACE W. HEYMAN, OF MAPLEWOOD, NEW JERSEY.

DRAFT CONTROL.

Application filed August 31, 1926. Serial No. 132,712.

It has been found desirable to provide a simple mechanism, for controlling a furnace, which can be located at a suitable place in the structure to be heated and which will enable the furnace control devices to be effectively operated when the temperature changes require.

Accordingly, an object of the present invention is to provide a structure which will not only mount the temperature indicating means, but also serve as part of the means for manually controlling the furnace draft system. This latter means is designed to be simple in operation and composed of but few parts, its simplicity of operation and construction making it far more desirable than a cumbersome automatic system which may require frequent repairs.

Reference will now be had to the accompanying drawings forming a part hereof for a more detailed description of the apparatus, wherein:

Figure 1 is a front elevation of one form of the invention.

Figure 2 is a side elevation, partly in section, of the device of Figure 1, taken on the line 2—2 of Figure 1.

Figure 3 is a plan view of the device of Figure 1.

Figure 4 is a rear elevation of the invention showing a modified form of pull rod, and,

Figure 5 is a plan, partly in section, of the modified form of pull rod.

In the drawings, and particularly in Figures 1, 2 and 3, *a* represents a wooden block secured to a wall by screws *b* and supporting a thermometer, shown at *c*. This thermometer may be of the usual form and will not be described in detail here.

The rear face of the block is provided with two countersunk flats *d* which receive a metal plate *e* so that the latter is flush with the rear face of the block. This will be seen from Figures 2 and 3. Between flats *d*, a channel *f* is provided to receive the slide *g*, permitting it to be retained by the plate *e* which is secured to the block by screws *e'*.

The upper end of slide *g* is bent to form a handle *g'* which is grasped by the operator to move the slide to a desired position. Having calibrations on its front face, the slide may be moved to any desired position demanded by the temperature of the room, and by means of the following structure, such movement is transmitted to the damper,

flues or other control elements of the heating system.

Below the groove *f*, a recess is provided to receive a metal strip *j* upon which seats a leaf spring *k* which bears against the slide *g* to hold it in any desired position.

The lower end of the slide is bent outwardly to form an arm *g''* and is provided with a hole *g'''* which receives a link *h* of a chain operating the above mentioned draft controls.

In the form shown in Figures 4 and 5, the arm *g''* is provided with a threaded extension *g'''*. An arm *i*, having a groove *i'* and a hole to receive the extension, is secured to the arm *g''*, the taps *g''''* holding the arm, and the groove *i'* receiving end of *g''* to prevent *i'* from turning. Arm *i* has a threaded extension *i''* and nut *i'''* secures the draft regulating connection thereto. In this form, obstacles in the wall which do not permit the chain to drop straight, are overcome.

Obviously, the material used may be varied, and the specific features of design changed without departing from the scope of this invention as set forth in the appended claims.

What I claim is:

1. In a draft control, a base, means for securing it to a wall, a manually operated slide for controlling the draft regulator of a heating plant, an outwardly projecting arm at the top of the slide for manual operation, an inwardly projecting arm at the bottom of the slide, means to connect the last named arm to the draft control means of a heating plant, a channel in the rear face of the base to receive the slide, and a countersunk plate secured to the rear face to slidably secure the slide to the base.

2. In a draft control, a base, means for securing it to a wall, a manually operated slide for controlling the draft regulator of a heating plant, an outwardly projecting arm at the top of the slide for manual operation, an inwardly projecting arm at the bottom of the slide, a threaded projection on the lower arm, a second arm having a hole to receive the projection and a groove to receive the end of the lower arm, means to secure the second arm to the projection, and means to connect the free end of the second arm to the draft control means.

3. As an article of manufacture, a draft control for a heating plant comprising a

base, means for securing it to a wall, a manually operable slide for controlling the draft regulator of the heating plant, an outwardly projecting arm at the top of the slide for manual operation, an inwardly projecting arm at the bottom of the slide, means to connect the last named arm to the draft control means of the heating plant, a channel in the rear face of the base to receive the slide, a recess in the channel, a leaf spring in said recess in frictional engagement with the slide to maintain the slide in any desired position, a countersunk plate secured to the rear face of the base to retain the slide with the channel, and marks on the slide to indicate the position of the draft regulator.

4. As an article of manufacture, a draft control for a heating plant comprising a base, means for securing it to a wall, a man-

ually operable slide for controlling the draft regulator of a heating plant, an outwardly projecting arm at the top of the slide for manual operation, an inwardly projecting arm at the bottom of the slide, a laterally projecting offset extension adapted to be attached to said last named arm, means to connect said extension to the draft control means of the heating plant, a channel in the rear face of the base to receive the slide, a recess in the channel, a leaf spring in said recess in frictional engagement with the slide to maintain the slide in any desired position, a countersunk plate secured to the rear face of the base to retain the slide with the channel, and marks on the slide to indicate the position of the draft regulator.

This specification signed this 27th day of August, A. D. 1926.

HORACE W. HEYMAN.
